UNITED STATES PATENT OFFICE.

LEONARD FREDERICK GEORGE BUTLER, OF BRISTOL, ENGLAND, ASSIGNOR OF ONE-THIRD TO ALBERT HUBERT ROY FEEDDEN AND ONE-THIRD TO COSMOS ENGINEERING COMPANY LIMITED, BOTH OF BRISTOL, ENGLAND.

BALANCING OF ENGINES.

1,340,823.

Specification of Letters Patent.

Patented May 18, 1920.

Application filed April 12, 1920. Serial No. 373,425.

To all whom it may concern:

Be it known that I, LEONARD FREDERICK GEORGE BUTLER, a subject of the King of England, residing at Bristol, in the county 5 of Gloucester, England, have invented certain new and useful Improvements in the Balancing of Engines, of which the following is a specification.

This invention is for improvements in or 10 relating to the balancing of engines, and while not limited to radial engines having several cylinders, is nevertheless more particularly applicable thereto.

As is well known the total load upon engine crank-pins due to inertia and centrifugal force, varies considerably both during 15 the cycle of rotation and during changes in the circumstances under which the engine is working. It is a difficult matter to counter-balance these forces exactly and attempts to do so by balance-weights fixed to the crank-shaft result in many cases in excessive bearing-loads being set up upon the crank-pin. To provide for these forces, in some cases 20 the crank-pin length has been increased, but this is not entirely satisfactory since the longer the pin, the greater is its liability to bend. The present invention therefore has for one of its objects to provide a method of 25 balancing engines which shall not necessarily increase the load upon the crank-pin, and the primary feature of the invention consists in the combination with an engine-connecting-rod-end of a balance-weight rotatably mounted on the connecting-rod-end, or a part rigid therewith, and attached to the crank-shaft to rotate therewith by a connection permitting of free movements toward and from the connecting-rod-end. 30

For a more complete understanding of the invention, reference is directed to the accompanying drawings which illustrate, by way of example only, one constructional form of balancing arrangement embodying 35 the above and other features of the invention.

In these drawings,

Figure 1 is a side elevation, partly in section, of a portion of the engine mechanism, 40 and

Fig. 2 is a front elevation of a balance-weight.

Like letters of reference indicate like parts throughout the drawings.

55 The mechanism illustrated is part of a

radial engine in which the cylinders are arranged in one plane, and in which a master connecting-rod is used in conjunction with auxiliary rods, the whole combination being connected to a single crank-pin. The 60 crank-shaft is shown at A, with cranks B and a crank-pin C. The main connecting-rod D is mounted at its end upon the crank-pin C and has additional wrist-pins E to which the auxiliary rods F are connected. 65 Rigid balance-weights or balancing extensions G of the usual type are illustrated as provided on the crank-shaft. These balance-weights G serve to counteract some of the forces set up during rotation of the engine. 70

To counteract other forces, without necessarily putting more load upon the crank-pin, there are provided, according to the present invention, further balance-weights 75 H. These balance-weights H are rotatably mounted at one end upon extensions D¹ on the connecting-rod D, suitable caps H¹ being provided on the balance-weights for this purpose. The balance-weights H are at 80 their other ends attached to the crank-shaft to rotate therewith by a connection permitting of free movement toward and from the end of the rod D. With the construction illustrated it will be seen that the bulk of 85 a balance-weight H is arranged adjacent one of the balancing extensions G and is connected thereto by a pin-and-slot connection. This connection comprises a bolt J with a nut J¹ and collar J², the latter being square 90 on the outside and being received in an elongated slot H² in the balance-weight.

In operation it will be seen that the centrifugal force set up in the balance-weights H, due to rotation of the crank-shaft, is free 95 to operate directly upon the connecting-rod-end D, D¹, that is, not through the intermediary of the crank-pin. Consequently, the load upon the latter is not necessarily increased by the balancing action of the 100 weights H. The elongated slots H² provide, further, that should any wear take place between the balance-weights and the connecting-rod extensions D¹, the weights will always be free to exert their pull directly upon 105 the connecting-rod-end.

It will be appreciated that the method of connecting the balance-weights to the crank-shaft to rotate therewith may be varied as desired, provided that the balance-weights 110

are still left free to exert their centrifugal force directly upon the connecting-rod or a part rigid therewith.

What I claim as my invention and desire

5 to secure by Letters Patent is:—

1. In a reciprocating engine the combination of a piston, a crank-shaft, a connecting-rod coupling them together, a balance-weight rotatively mounted on that end of
10 the connecting-rod which is secured to the crank-shaft, and means coupling said balance-weight to said crank-shaft to cause it to rotate therewith, but permitting free movement of said weight toward and away
15 from the connecting-rod end.

2. In a reciprocating engine the combination of a piston, a crank-shaft, a balance-weight fixed on said crank-shaft, a connecting rod coupling said piston to said crank-
20 shaft, a balance-weight rotatively mounted on the end of the connecting-rod and situ-

ated adjacent said fixed balance-weight, and a pin-and-slot connection whereof the slot is radial to the crank-shaft between said two balance-weights.

3. In a reciprocating engine, the combination of a crank-shaft, a plurality of cylinders, a piston in each of said cylinders, a master connecting-rod coupling one of said pistons to said crank shaft, auxiliary connecting-rods articulated to said master connecting-rod and connected one to each of said other pistons, a balance-weight rotatively mounted on the big end of said master connecting-rod on an axis parallel with the axis of said crank-shaft, and means coupling said balance-weight to said crank-shaft to rotate therewith, but permitting free movement of said weight radially to said crank-shaft.

40 In testimony whereof I affix my signature.

LEONARD FREDERICK GEORGE BUTLER.
